The ornamental design for a tabletop horseshoe game and container therefor, as shown and described.

DESCRIPTION

FIG. 1 is a top plan view of a tabletop horseshoe game and container therefor showing my new design; the bottom plan view being a mirror image thereof; FIG. 2 is a left side elevational view thereof; the right side elevational view being a mirror image thereof; FIG. 3 is a perspective view thereof;

FIG. 4 is a left side elevational view of a second embodiment of FIG. 1;

FIG. 5 is a right side elevational view of FIG. 4;

FIG. 6 is a top plan view of FIG. 4;

FIG. 7 is a bottom plan view of FIG. 4;

FIG. 8 is a front elevational view of FIG. 4; and,

FIG. 9 is a rear elevational view of FIG. 4.

The rear surface of FIG. 1 embodiment is plain and unornamented.

FIG. 2

FIG. 1

FIG. 3

FIG. 4

FIG. 5

FIG. 6

FIG. 9

FIG. 8

FIG. 7
